Inventor
Louis A. Negralval
By his Attorney
Charles R. Searle

UNITED STATES PATENT OFFICE.

LOUIS A. NEGRAVAL, OF JERSEY CITY, NEW JERSEY.

JEWELRY-BOX.

1,367,322.

Specification of Letters Patent.

Patented Feb. 1, 1921.

Application filed May 3, 1920. Serial No. 378,536.

To all whom it may concern:

Be it known that I, LOUIS A. NEGRAVAL, a citizen of the United States, residing at Jersey City, in the county of Hudson and State of New Jersey, have invented a certain new and useful Improvement in Jewelry-Boxes, of which the following is a specification.

The invention relates to ornamental boxes intended to contain articles of jewelry and the like, and the object of the invention is to provide a box combining lightness and strength, which may be easily and cheaply manufactured, not liable to distortion by changes in atmospheric conditions, eminently durable, and neat and attractive in appearance.

The invention consists in certain novel features of construction and arrangement of parts by which the above objects are attained, to be hereinafter described and claimed.

The accompanying drawings form a part of this specification and show the construction of the improved box, with the ornamental lining, covering, and other accessories omitted.

Figure 1 is a plan or top view of a box embodying the invention.

Fig. 2 is a rear elevation of the same.

Fig. 3 is a corresponding side view.

Fig. 4 is a longitudinal vertical section taken on the line 4—4 in Fig. 1.

Fig. 5 is a transverse section, taken on the line 5—5 in Fig. 1.

Fig. 6 is a horizontal section and plan, taken on the line 6—6 in Fig. 5.

Fig. 7 is a face view of a metal strip forming the frame of the lower box-member, before bending.

Fig. 8 is a face view of a lining strip to be applied within the frame in the assembling operation.

Fig. 9 is a vertical section on a larger scale showing the lining strip and bottom disk in position relatively to the frame before engagement by the latter.

Fig. 10 is a corresponding view showing the same parts engaged.

Fig. 11 is a horizontal section through the rear wall of the lower box-member.

Similar letters of reference indicate the same parts in all the figures.

The box comprises an upper and a lower member hinged together at the rear. The lower member is made up of a strip of metal

A bent to form a frame having the shape of the box in plan and shown as rectangular, with the ends abutting or lying adjacent each other at the center of the rear face as 60 at the open joint *a*.

Within the frame is a disk B serving as the bottom of the box, matching to the frame and preferably of fiber board or other strong but light material, and a lining strip C of 65 the same or like material, bent to rectangular form, resting upon the disk B and fitted snugly to the inner face of the frame. Its ends abut at the front as at *c* opposite to the frame junction *a* so as to break joints with 70 the latter. The disk B and lining strip C are held by folding the upper and lower margins of the metal frame A upon the upper edge of the strip C, and upon the lower margins of the disk B respectively. 75

The upper portion or member of the box may be similarly shaped and assembled but is shown as having its disk or top E swelled or domed, and resting on a lining strip F, 80 inclosed in a frame D and held by folding the margins of the frame upon the margins of the disk E and beneath the lower edge of the strip F. The frame joint *d* is at the rear and the strip joint, not shown, is at the front. 85

So far as described the lining strips C and F and bottom disk B and top disk E are retained only by the shape and stiffness of the frames A and D; to lock the abutting ends of the metal frames at the joints *a* and *d* a 90 staple is passed from the exterior of each frame to the interior and its ends folded down.

Slots *a*¹ provided in the lower frame A near its ends receive the arms of the staple G which also pass through slots *c* at the midlength of the paper lining strip C, and through slots *j* in the lower leaf of a hinge J, and are folded upon the face of the leaf, as shown in Fig. 11, and tightly clenched 100 thereon. A similar staple H is inserted in like manner through the frame D and strip F and clenched upon the face of the upper leaf of the hinge J.

Thus joined, the upper and lower box-members are each securely locked upon their disks and lining strips, and both are reliably held to the hinge without other fastening means. Notches *a*² at the ends of the lower frame, see Fig. 7, and similar 110 notches *a*² in the upper frame provide for the reception of the barrel of the hinge.

Fig. 9 shows the metal strip A with its bottom disk B and paper lining strip C in position before the margins of the strip or frame A are folded by suitable dies upon these contained parts, and Fig. 10 shows the condition of the same parts after the folding operation. The fold should extend sufficiently beneath the disk B to insure sufficient hold and should extend across the upper edge of the lining strip C to protect such edge and form a smooth finish.

The hinge J is shown as equipped with a spring J¹ arranged to hold the box in the open or in the closed condition, but this feature may be omitted or other forms of spring hinges employed.

The lining strips C and F may be as thick as desired in producing an effect of solidity without materially affecting the weight of the box, and by making the frames of metal and the disks and lining strips of lighter material, the desired strength and rigidity is attained with a minimum of weight. The metal frames locked upon the paper parts insure against warping or distortion of such parts, and maintain the box members in proper relation to each other through the positive engagement with the leaves of the hinge.

It will be understood that the box may be equipped with jaws and forms for the reception of the article to be held, and may be lined and covered with any desired rich material adapted to provide the required finish and enhance the appearance.

Modifications may be made in the forms and proportions of the parts without departing from the principle of the invention. The top E may be flat similar to the bottom B or these parts and the contour of the box may be varied as desired or dictated by the shape of the article to be inclosed.

I claim:

1. A box member comprising a disk, a non-metallic lining strip with one edge mounted upon adjacent face of said disk, a metallic frame surrounding said lining

with its opposite edges bent parallel with and engaging the opposite face of said disk and the one exposed edge of said lining strip, and means passed through said lining strip and frame and joining the ends of the latter.

2. The box member described, comprising a disk, a lining strip mounted on edge at the margins of said disk, a metal frame inclosing said strip and edges of said disk, with the margins of said frame folded upon said disk-margins and the exposed edge of said strip, and with the ends of said frame lying adjacent each other, a hinge applied on said box member, and fastening means extending through said ends, strip, and hinge, for joining said ends and holding said box member to said hinge.

3. The box member described, comprising a disk, a lining strip mounted on edge at the margins of said disk, a metal frame inclosing said strip and edges of said disk, with the margins of said frame folded upon said disk-margins and the exposed edge of said strip, and with the ends of said frame lying adjacent each other, a hinge applied on the interior of such box member, and a staple having its arms extended through said ends, strip, and hinge, and folded upon the latter.

4. The box described, comprising an upper and lower box member, each consisting of a disk, a lining strip, and a metal frame inclosing said disk and strip, with its margins folded upon said disk and strip, a hinge on the interior of such box, a staple having its arms extended through the adjacent ends of such upper frame, strip and hinge-leaf and folded upon such leaf, and a second staple having its arms extended through the adjacent ends of such lower frame, strip and hinge-leaf and folded upon the latter.

In testimony that I claim the invention above set forth I affix my signature.

LOUIS A. NEGRAVAL.
